Primary Examiner — Lauren Calve(74) *Attorney, Agent, or Firm* — Jonathan Grant; Grant Patent Service(57) **CLAIM**

The ornamental design for a jewelry hanger, as shown and described.

DESCRIPTION

FIG. 1—is a perspective view of a jewelry hanger;

FIG. 2—is a front view thereof;

FIG. 3—is a back view thereof;

FIG. 4—is an underside view thereof;

FIG. 5—is a top view thereof;

FIG. 6—is a front side view thereof; and,

FIG. 7—is a back side view thereof.

It will be understood that the dashed lines presented in the drawings are for illustration only, and do not form a part of the claimed design.

The broken lines shown represent unclaimed subject matter and form no part of the claimed design.

1 Claim, 5 Drawing Sheets(56)
